CIGARETTE VENDING MACHINE

Egbert C. Jenner, Independence, Mo.

Application September 28, 1953, Serial No. 382,775

7 Claims. (Cl. 194—2)

This invention relates to machines particularly adapted for vending cigarettes not only in the package form but individually, the primary object being to provide inexpensive, simple, positively operating mechanism for automatically dispensing a single cigarette to a customer each time he purchases and receives a package of cigarettes.

It is an important object of the present invention to provide a cigarette vending machine that may be associated with a napkin holder or the like on a restaurant counter or table and which includes a cabinet for receiving not only a stack of cigarette packages but a single open package, making available cigarettes therewithin for automatic vending one at a time as the packages are removed singly from the stack therebelow.

Another object of the invention is to provide a vending machine for cigarettes having a means for vending cigarettes individually, thereby permitting the advertising to the purchaser through sampling another kind of cigarette or commodity than those sold through the machine in packages, which means is coupled with the primary mechanism for vending the packages of cigarettes, in such a way that the individual cigarettes or commodity may be purchased separately upon insertion of a suitable coin.

Other objects include the way in which the cigarette vending machine is equipped with an ejector plate having a rough, uppermost surface supporting the stack of cigarette packages for withdrawing the lowermost package each time the primary coin control mechanism is operated; the way in which a coin-receiving plate actuator or plunger is automatically restricted so far as inward movement is concerned whenever the same is operated in absence of a coin; the manner in which the apparatus for limiting movement of the actuator also operably engages the ejector plate to prevent outward movement of the latter; and many additional objects including important details of construction, all of which will be made clear as the following specification progresses.

In the drawings:

Figure 1 is a front elevational view of a cigarette vending machine made pursuant to my present invention, parts being broken away to reveal details of construction.

Fig. 2 is a longitudinal, vertical, cross-sectional view taken on line II—II of Fig. 1.

Fig. 3 is a fragmentary, detailed, cross-sectional view taken on line III—III of Fig. 2.

Fig. 4 is a vertical, cross-sectional view taken on line IV—IV of Fig. 2.

Fig. 5 is a cross-sectional view taken on line V—V of Fig. 2.

Fig. 6 is a fragmentary, cross-sectional view taken on irregular line VI—VI of Fig. 5.

An elongated, upright cabinet, broadly designated by the numeral 10, is clearly illustrated in Figs. 1 and 2 of the drawings and formed to present a compartment 12 for storage of a number of packages of cigarettes 14, stacked upon an ejector plate 16 carried by the cabinet 10 for horizontal reciprocation. This cabinet 10 may advantageously be associated with a napkin holder 13 that usually forms a part of the standard equipment of restaurant tables and counters.

A downwardly and forwardly inclined partition 18 within the cabinet 10, defines a chamber 20 thereabove adapted to receive a single package 22 of cigarettes 24. Package 22 is normally opened when placed in the chamber 20 so that the cigarettes 24 thereof will gravitate toward a chute 26 exteriorly of the cabinet 10 and constituting an extension of the partition 18. The top wall 28

2

of the cabinet 10 is preferably transparent so that an observer may see that seal 30 of the package 22 has been broken.

5 An access opening in the back of the cabinet 10 is provided to permit replenishing of the packages 14 and the single package 22, which access opening is normally closed by a swingable door 32.

The individual cigarettes 24 adapted to gravitate along the partition 18 toward the chute 26, are normally held against such movement by a cradle 34 swingably mounted within the cabinet 10 and yieldably held in the position illustrated in Fig. 2 of the drawings by a spring 36. Spring 36 interconnects the cabinet 10 and a laterally extending arm 38 depending from the cradle 34 and against the innermost end of a guide channel 40 for a manual slide 42.

20 Channel 40 is provided with a slot 44 (see Fig. 3) for receiving a coin 46 which, when inserted in the slot 44, may be brought against the arm 38 by inward movement of the slide 42 to swing the cradle 34 to a position permitting a single cigarette 24 to roll from the chamber 20 into the chute 26 where the same is accessible to the customer. When the coin 46 reaches the innermost end of the guide channel 40, it drops into a passageway 48 (see Figs. 1 and 5) to a coin collection box 50 forming a part of cabinet 10, it being noted that the coins may be removed from the box 50 upon opening of door 32.

30 A sheet of sandpaper, emery cloth or other frictionable material 51, is provided on the uppermost face of ejector plate 16 and upon which the lowermost package 14 of cigarettes normally rests. Thus, when the plate 16 is shifted along opposed tracks 52 outwardly or to the left, viewing Figs. 2, 5 and 6, the said lowermost package 14 will be withdrawn from beneath the stack through an outlet opening 54 formed in the cabinet 10.

35 An elongated link 56 swingably mounted as at 58 with-in the passageway 48 of cabinet 10, is attached to the plate 16 by a pivot pin 60 and connected at its uppermost end with the arm 38 by an element 62 so that the cradle 34 is actuated automatically each time the ejector plate 16 is withdrawn from the position shown in Fig. 2. The element 62 is preferably flexible so that the cradle 34 may be operated independently of the plate 16 upon insertion of coins 46 in slot 44.

40 The plate 16 slides upon a horizontal wall 64 immediately below tracks 52, the latter of which take the form of grooves, and a slide panel 66 spaced below the wall 64 defines the uppermost wall of coin box 50. The panel 66 is provided with a hole 68 and slidably receives a plunger or actuating member 70 for the plate 16. Member 70 is provided with a coin-receiving perforation 72 disposed for alignment with coin clearance hole 68 when the member 70 is shifted inwardly toward a stop 74. A spring 76 interconnecting the member 70 on the cabinet 10, yieldably holds the member 70 biased at the outermost end of its path of travel.

45 The mechanism for operably interconnecting the plate 16 and the plunger member 70 is located in its entirety between the plate 16 and the member 70 or the panel 66. It includes a pinion 78 rotatably mounted on the panel 66, together with a first rack 80 secured to the lowermost face of plate 16 and a second rack 82 mounted on the upper face of member 70. Rack 80 is in mesh with the pinion 78 and the rack 82 moves into meshing engagement therewith when the plunger 70 is moved inwardly toward the stop 74.

50 Apparatus for forcing utilization of a coin in the perforation 72 in order to operate the ejector plate 16 by use of member 70, is likewise located between the wall 64 and the panel 66. It includes an elongated bar 84 mounted on a shaft 86 for swinging movement on a horizontal axis and yieldably biased toward one end of its path of travel by a leaf spring 88 on the stop 74.

55 When the member 70 is moved inwardly in absence of a coin within the perforation 72, spring 88 will automatically force an ear 90 into the perforation 72 and thereby prevent further inward movement of the member 70. Simultaneously, a lug 92 on the opposite end of the bar 84 moves into a cavity 94 within the plate 16 to prevent outward movement of the latter.

In normal operation, a coin is inserted in the perforation 72 and the operator moves the plunger 70 inwardly until the rack 82 meshes with the pinion 78. Such coin slides beneath the ear 90 preventing operation of the locking apparatus until it is discharged into the box 50 by way of the clearance hole 68. Further inward movement of the plunger 70 rotates the pinion 78 by operation of rack 82 and such rotation of pinion 78 in turn shifts the rack 80 in the opposite direction to move the plate 16 outwardly along groove tracks 52. By virtue of the roughened nature of the uppermost surface of plate 16 through the material 51, the lowermost pack 14 of cigarettes will be pulled through the opening 54 to a position where the same may be grasped and entirely removed from the cabinet 10.

Simultaneously, with outward movement of the plate 16 the link 56 will be swung on its pivot 58 to pull out element 62, thereby swinging the arm 38 inwardly and actuating the cradle 34 to eject a single cigarette 24 into the chute 26.

Springs 36 and 76 will automatically return the cradle 34 and the plunger member 70 respectively to the normal position shown in Fig. 2 of the drawings when the plunger 70 is thereupon released by the operator.

Having thus described the invention what is claimed as new and desired to be secured by Letters Patent is:

1. In a cigarette vending machine, a cabinet; a horizontally reciprocable ejector plate carried by the cabinet and having a rough, uppermost surface, said cabinet having a compartment for storage of a number of packages of cigarettes on said surface of the plate, there being an outlet opening in the cabinet above the plate in alignment with the lowermost package of said stack; a partition in the cabinet terminating in a chute exteriorly of the cabinet and defining a chamber thereabove for receiving a single package of cigarettes, said partition being inclined for gravitation of cigarettes toward the chute from the single package when the latter is open; a cigarette-receiving cradle disposed to normally hold the cigarettes of the single package within the chamber; means mounting said cradle in the cabinet for swinging movement to and from a position releasing cigarettes singly from the chamber to said chute; and structure operably connecting the plate with the cradle for swinging the latter to said position each time the plate is moved to one end of its path of travel to withdraw a package of cigarettes from said compartment through the outlet opening.

2. A cigarette vending machine as set forth in claim 1 wherein said structure includes a link swingably secured to

the cabinet and pivotally joined to the plate, and an element coupling the cradle with the link, said element being flexible to permit swinging of the cradle to and from said position independently of the plate.

5. A cigarette vending machine as set forth in claim 1 wherein said cradle is provided with a lateral arm depending therefrom, and wherein means is provided to force a coin into the cabinet and against the arm to swing the cradle to said position, and resilient means interconnecting the arm and the cabinet for yieldably holding the cradle biased in its normal cigarette-holding position.

10. A cigarette vending machine as set forth in claim 1 wherein is provided a plate-actuating member reciprocably carried by the cabinet, and mechanism between the plate and the member for operably interconnecting the same to move the plate to said one end of its path of travel upon movement of the member inwardly into the cabinet.

15. A cigarette vending machine as set forth in claim 4 wherein said mechanism comprises a pinion rotatably carried by the cabinet between the plate and the member, a first rack mounted on the lowermost face of the plate in mesh with the pinion, and a second rack mounted on the uppermost face of the member in alignment with the pinion for meshing engagement therewith upon inward movement 20 of the member.

25. A cigarette vending machine as set forth in claim 4 wherein said cabinet has a slide panel underlying the member and provided with a coin clearance hole, there being a coin-receiving perforation in the member disposed for alignment with the hole upon movement of the member toward the innermost end of its path of travel, and apparatus carried by the cabinet for movement into the perforation when the latter is moved inwardly in absence of a coin in the perforation to limit the extent of inward movement 30 of the member.

35. A cigarette vending machine as set forth in claim 6 wherein said apparatus includes a bar swingably mounted in the cabinet between the plate and the member and having an ear on one end thereof engageable in said perforation when the bar swings to one end of its path of travel, there being a cavity in the plate and a lug on the opposite end of the bar, said lug extending into the cavity when the ear is in the perforation, and resilient means mounted in the cabinet and engaging the bar for yieldably holding the 40 same biased toward said one end of its path of travel.
